CASING MEMBERS OF VACUUM CLEANERS
AND LATCHES THEREFOR

Edgar P. Turner, Fanwood, N. J., assignor to The Singer Manufacturing Company, Elizabeth, N. J., a corporation of New Jersey

Application March 24, 1948, Serial No. 16,716

14 Claims. (Cl. 220—4)

1
This invention relates to vacuum cleaners and more particularly to a latch means by which the upper and lower casing shells of a vacuum cleaner can be fastened together, and one of the primary objects of the invention is to provide an improved device of this class.

Another object of the invention is to provide a single latch means that is arranged to hold the lower shell of a vacuum cleaner casing securely to the upper shell.

Still another object of the invention is to provide an improved vacuum cleaner latch that can easily be manipulated by a housewife without the use of tools or other special equipment.

With these and other objects in view, as will hereinafter appear, the invention consists in the devices, combinations and arrangements of parts described in connection with the accompanying drawings, which illustrate a preferred embodiment of the invention and in which:

Fig. 1 is a side elevational view of a vacuum cleaner embodying a preferred form of this invention;

Fig. 2 is a fragmentary sectional view of the vacuum cleaner casing and taken substantially on the line 2—2 of Fig. 1;

Fig. 3 is an inverted perspective view of a portion of the vacuum cleaner shown in Figs. 1 and 2, the upper and lower shells of the cleaner being fastened together by the latch of this invention; and

Fig. 4 is a view similar to Fig. 3 except that the latch members are disengaged and the upper and lower casing shells are separated.

Referring in detail to the drawings, the illustrated embodiment of the invention is shown as applied to a vacuum cleaner having an ambulatory casing 11 formed from an upper casing shell 12 having vertical walls 12^a and a lower casing shell 13 having vertical walls 13^a; the two shells being joined on a line indicated by the numeral 14. The lower casing shell 13, which is substantially U-shaped when seen in plan view, is fastened to the upper casing shell 12 by a latch or catch means 16 hereinafter described. The shell 12 is also U-shaped, in that it is formed to be joined by the shell 13, but instead of being open between the arms of the U, the shell 12 is closed by a top plate 12^b.

A combination electric motor and fan unit 17 is supported in the casing shells and the whole vacuum cleaner moves on front and rear wheels 18 and 19. The front wheels 18 are rotatably supported from the lower casing shell 13, and the rear wheels 19 are rotatably carried by an exhaust duct 21 formed integral with a portion of the motor-fan unit 17.

A guiding and propelling handle 22 is pivotally carried by the vacuum cleaner in a manner more fully described in my prior United States

patent application Serial No. 784,167, filed November 5, 1947. A dust bag 23 is attached, in any convenient manner, to the open outlet end of the exhaust duct 21, and the upper end of this bag is supported from the handle 22 in a manner not herein shown.

2
The latch 16, used for fastening the lower shell 13 to the upper shell 12, includes a long flat steel spring 24 and a wire hook 25. Substantially medianly of its length, the spring 24 is transversely provided with a downwardly projecting U-shaped bend 26. The extreme ends 24^a—24^a of the spring 24 are clamped between downwardly projecting bosses 27, formed integral with the upper casing shell 12, and ribs 28, protruding from the motor-fan unit 17; the ribs 28 being held to the bosses 27 by screws 29. A rib 31 is formed integral with and depends from a central portion of the upper shell top-plate 12^b, and this rib is provided on its lower or free end with a concave seat 32 disposed within the bend 26. When the latch 16 and the spring 24 are in the unlatched position, shown in Figs. 2 and 4, the U-shaped bent portion 26 of the spring 24 fits over the lower end of the rib 31. The bent portion 26 and the seat 32 journal a horizontally extending straight axle-portion 33 of the hook 25. The hook 25 and a handle portion 36 are formed integral with and depend substantially at right angles, from opposite ends of the straight portion 33. The hook 25 is substantially L-shaped in form and has a crooked end 38. The hook 25 and its end 38 are so constructed and arranged that they can be made to engage a channel 39 formed in the lower surface of an oval shaped lug or keeper 41 that protrudes horizontally from an appropriate portion of the lower shell 13. Preferably the spring 24 is preloaded to such an extent that, when the hook 25 is in the unlatched position (Fig. 4) no initial movement of the latch will be required to bring the spring to a requisite clamping pressure.

Reference to Fig. 1 shows that the latch 16 is positioned substantially midway between the front and rear edges of the shells 12 and 13, and reference to Figs. 2, 3 and 4 shows that the latch 16 is also positioned midway between the side edges of these shells. This is an important factor in making it possible to fasten the two casing shells together by the use of a single latch securing means.

If the upper and lower casing shells 12 and 13 are separated, as shown in Fig. 4, they can be fastened together by the latch or catch 16. To accomplish this, the vacuum cleaner is placed in the inverted position shown in Fig. 4 with the bottom shell 13 on top of the upper shell 12, and with the hook 25 resting on a stop 42 formed integral with the upper shell 12. The vertical walls 13^a of the lower shell 13 are moved into

register with the vertical walls 12^a of the upper shell 12. Then the handle portion 36 of the latch 16 is moved counterclockwise, as seen in Figs. 3 and 4. This causes the end 38 of the hook 25 to engage the channel 39 of the lug 41. The crooked end 38 acts as a cam, and raises the hook 25 and its straight portion 33 against the tension of the spring 24. As the end 38 of the hook moves along the channel 39 of the lug 41, the straight portion 33 of the hook 25 and U-shaped portion 26 of the spring 24 move away from the concave seat 32 of the rib 31. As the handle 36 continues to move counterclockwise as seen in Figs. 3 and 4, the hook portion 25 finally assumes the position shown in Fig. 3, wherein the hook 25 fully engages the lug 41. Under these conditions, the spring 25 is flexed and securely holds the lower shell 13 to the upper shell 12.

Having thus set forth the nature of the invention, what I claim herein is:

1. In a vacuum cleaner, an upper casing shell having front, rear and a pair of spaced side edges, a U-shaped lower casing shell arranged to cooperate with said upper casing shell to form a complete vacuum cleaner casing, and a single latch arranged to fasten said casing shells together, said latch being located centrally between said front and rear edges and centrally between said pair of spaced side edges.

2. In a vacuum cleaner having an upper casing shell provided with front, rear and a pair of spaced side edges and a U-shaped lower casing shell arranged to cooperate with said upper casing shell to form a complete vacuum cleaner casing, a latch member on one of said shells, a second latch member on the other of said shells, and a third latch member arranged to connect said first and second latch members; two of said latch members being centrally located with respect to said front and rear edges and also with respect to said spaced side edges.

3. In a vacuum cleaner, an upper casing shell, a U-shaped lower casing shell arranged to cooperate with said upper casing shell to form a complete vacuum cleaner casing, spaced front and rear edges and spaced side edges for one of said casing shells, a latch arranged to engage one of said casing shells at a location positioned centrally between said front and rear edges and also centrally between said spaced side edges, and a spring arranged to bias said latch, said spring being connected to said other casing shell.

4. In a vacuum cleaner having a casing formed from an upper casing shell and a lower casing shell, a single connecting means arranged to fasten said casing shells together, said single connecting means comprising a spring secured to one of said casing shells, a latch member carried by said spring, and a cooperating latch member secured to the other casing shell.

5. In a vacuum cleaner having a casing formed from an upper casing shell and a lower casing shell, a single latch arranged to fasten the casing shells together, the latch comprising a flat steel spring secured at both of its ends to one of said casing shells, a wire latch member formed into the shape of a hook and carried by said spring, and a second latch member engageable by said hook, said second latch member being secured to the other casing shell.

6. In a vacuum cleaner having a casing formed from an upper casing shell and a lower casing shell, a single latch arranged to fasten the cas-

ing shells together, said latch being located centrally of the casing shells, the latch comprising a flat steel spring bent at its midpoint and secured at both of its ends to one of said casing shells, a latch member journaled in the bent portion of said spring, and a cooperating latch member in the form of a channelled lug carried by the other casing shell.

7. In a vacuum cleaner having a casing formed from an upper casing shell and a lower casing shell, a latch arranged to fasten the casing shells together; the latch comprising, a protruding lug carried by one of said casing shells, a flat-spring bent at its center and secured at both of its ends to the other casing shell, and a bent wire hook carried by said spring, and having a handle at one of its ends and a cam-like crook at the other end, the hook being so constructed and arranged as to engage said lug.

8. In a vacuum cleaner having a casing formed from an upper casing shell and a lower casing shell, a latch arranged to fasten the casing shells together; the latch comprising, a channelled lug carried by one of said casing shells, a flat-spring provided medially of its length with a U-shaped bend and secured at both of its ends to the other casing shell, and a bent wire member having a straight portion journaled in said U-shaped bend, a handle at one end of said straight portion and a cam-like hook at the other end thereof, the hook being so constructed and arranged as to engage said lug.

9. In a vacuum cleaner having a casing formed from an upper casing shell and a lower casing shell, a latch arranged to fasten the casing shells together; the latch comprising, a protruding lug carried by a first of said casing shells, a flat-spring bent at its center and secured at both of its ends to a second of said casing shells, a rib depending from the second casing shell and having a concave seat in its free end, and a bent wire hook carried by said spring and having a handle at one of its ends and a cam-like crook at the other end, the hook being so constructed and arranged as to engage said concave seat when the latch is unlatched and to engage said lug when the latch is latched.

10. In a vacuum cleaner having a casing formed from an upper casing shell and a lower casing shell, a latch arranged to fasten the casing shells together, the latch comprising a channelled lug protruding horizontally from one of said casing shells, a flat preloaded spring bent at its center and secured at both of its ends to the other casing shell, and a bent wire having a straight portion journaled in said bent portion of said spring and having a hook portion and a handle portion depending from the straight portion, the hook portion being so constructed and arranged as to engage said lug and force said casing shells toward one another when said handle portion is properly manipulated.

11. In a vacuum cleaner having a casing formed from an upper casing shell and a lower casing shell, a latch arranged to fasten the casing shells together, the latch comprising a channelled lug protruding horizontally from one of said casing shells; a flat preloaded spring having a U-shaped bend at its center and secured at both of its ends to the other casing shell; a bent wire having a straight portion journaled in said U-shaped bend of said spring, a hook portion having a crooked end, and a handle portion depending from the straight portion, the hook portion being so constructed and arranged as to engage

said lug and force said casing shells toward one another when said handle portion is manipulated.

12. In a vacuum cleaner having a casing formed from an upper casing shell and a lower U-shaped casing shell, a latch arranged to fasten the casing shells together, the latch comprising a single channelled lug protruding horizontally from said lower casing shell, a single flat pre-loaded spring having a depending U-shaped bend medianly of its length, the spring being secured at both of its ends to the upper casing shell; a single rib depending from said upper shell and having on its lower end a concave seat disposed within the U-shaped bend in said spring, a single straight wire journaled by said concave end and said U-shaped bend in said spring, a single hook depending from one end of said straight wire and arranged to engage said lug, a single operating handle depending from the other end of said straight wire and arranged to move said hook; said hook and said lug when in engagement being arranged to hold the lower casing shell securely to said upper casing shell.

13. A vacuum cleaner casing comprising, complementary shell-members, a flat-spring having its opposite ends secured to one of said shell-members and transversely provided substantially medianly of its length with a U-shaped bend, a latch member pivotally mounted in said U-shaped bend

of the spring, and a keeper carried by the other of said shell-members in position for engagement by said latch member, said spring biasing said latch away from said keeper.

14. A vacuum cleaner casing comprising, complementary shell-members, a flat-spring having its opposite ends secured to a first one of said shell-members and transversely provided substantially medianly of its length with a U-shaped bend, a rib extending from said first one of said shell-members into said U-shaped bend, a latch member pivotally disposed between said rib and bend, and a keeper carried by a second one of said shell-members in position for engagement by said latch member, said spring biasing said latch away from said keeper.
